UNITED STATES PATENT OFFICE.

ALBERT C. LINK, OF DETROIT, MICHIGAN.

GOLF CLUB.

Application filed November 3, 1927. Serial No. 230,770.

The main objects of this invention are:

First, to provide a golf club in which the weight is so disposed that its shock or driving force is centered approximately in the 5 center of the striking face.

Second, to provide a golf club in which the weight is disposed so as to provide a well balanced club, at the same time effectively centering the weight in the striking 10 face as the blow is delivered.

Objects relating to details and economies of my invention will appear from the detailed description to follow. The invention is defined and pointed out in the claims.

15 A structure which is a preferred embodiment of my invention is illustrated in the accompanying drawing, forming a part of this specification, in which:

Fig. 1 is a rear perspective view of my 20 improved golf club, the shank being broken away.

Fig. 2 is a plan view.

Fig. 3 is a central vertical section from front to rear of the club.

25 Fig. 4 is an inside perspective view of the weight.

Fig. 5 is a detail section on a line corresponding to line 5-5 of Fig. 3.

Fig. 6 is a detail view on a line corresponding to line 6-6 of Fig. 3.

In the drawing similar reference characters refer to similar parts throughout the several views.

Referring to the drawing, the head 1 is 35 preferably formed of wood and is provided with a striking face designated generally by the numeral 2, this striking face illustrated being that of my copending application for Letters Patent filed October 22nd, 1927, Serial No. 227,948.

The rear edge of the head is formed with 40 two segmentally curved surfaces 3 and 4 disposed at an angle to each other, the surface 3 being downwardly and rearwardly inclined while the surface 4 is upwardly and rearwardly inclined to meet in an angle at 5, this angle being in approximately the horizontal center of the rear portion of the head. Both of these surfaces center approximately 45 in a vertical plane through the center of the striking face.

The weight comprises a pair of wing-like members 7 and 8, their inner faces being curved to conform to the curves of the sur-

faces 3 and 4 respectively, the weight being 55 secured to the head by means of the wood screws 9.

The wing members of the weight are tapered towards each end from a point lying in the plane of the vertical center of the 60 striking face, the exterior surface of the weight being co-incident with or complementary to the rear surface of the club.

With the weight thus shaped and arranged, it is distributed in a radial relation 65 to the center of the striking face, the top or upward portion of the weight transmitting its shock downwardly and centrally relative to the center of the striking face while the lower portion of the weight transmits its shock upwardly and centrally relative to such center, thereby securing a much desired balance, the entire shock or momentum of the weight being delivered to such center. 70

I have not attempted to illustrate or describe my improvements in certain modifications or adaptations that might be desirable in the event of modifying or adapting this to clubs having heads of other shape as the 80 head illustrated is what might be designated as standard type and it is believed that the disclosure made will enable those skilled in the art to modify or adapt my improvements as may be desired. 85

Having thus described my invention, what I claim as new and desire to secure by Letters Patent, is:

1. In a golf club, the combination of a 90 head member having its rear edge conformed to provide two curved surfaces of substantial arc centering at approximately the center of the striking face and meeting at an angle in approximately the horizontal center of the head, and an integral weight comprising 95 two segmental wing-like members disposed at an angle to each other and curved on their inner faces to correspond to and clamped upon said curved surfaces of said head. 100

2. In a golf club, the combination of a head member having its rear edge conformed into two curved surfaces disposed at an angle to each other in rearwardly inclined relation and centering approximately in the center 105 of the striking face of the head, and a weight conformed to and secured upon said surfaces, said weight being tapered from a central

point towards each end, such central point being in approximately the vertical plane of the center of the head.

3. In a golf club, the combination of a head member having its rear edge conformed into two outwardly curved surfaces disposed at an angle to each other in rearwardly inclined relation and with their radii centering approximately in the center of the striking face of the head, and a weight conformed to and secured upon said surfaces whereby the impact of the weight is delivered radially towards the center of the striking face.

4. In a golf club, the combination of a head member having its rear edge conformed into outwardly and horizontally curved surfaces disposed at an angle to each other and with their radii centering at approximately the center of the striking face of the head,

and a segmental weight conformed to and secured upon said surfaces, said weight being tapered from a central point towards each end, such central point being in the vertical plane of the center of the head.

5. In a golf club, the combination of a head member having its rear edge conformed into outwardly and horizontally curved surfaces disposed at an angle to each other and with their radii centering at approximately the center of the striking face of the head, and a segmental weight conformed to and secured upon said surfaces whereby the impact of the weight is delivered radially towards the center of the striking face.

In witness whereof I have hereunto set my hand.

ALBERT C. LINK
